UNITED STATES PATENT OFFICE

2,218,313

WRENCH

Glen W. Hamilton, Kansas City, and Vinton H. Rowlett, St. Louis, Mo.

Application December 10, 1937, Serial No. 179,145

1 Claim. (Cl. 81—86)

This invention relates to improvements in wrenches and has for its principal object the provision of a tool suitable for entirely encircling and clamping an article whereby it may be 5 forcibly moved to or from a predetermined position.

Another object of the invention is the provision of a wrench comprising a relatively thin body portion with a transverse opening formed therethrough for the reception of an article to be clamped, and a jaw slidably mounted in said body portion movable to vary the size of said opening and to engage the article positioned therein.

15 A further object of this invention is the provision of a wrench having the engaging portion thereof arcuate to facilitate the engagement of nuts, or similar articles, positioned on planar surfaces.

20 Other objects are sturdiness of construction, and ease of operation. With these and other objects in view, which will appear during the course of the specification, reference will now be had to the drawing wherein:

25 Figure 1 is a plan view of a wrench embodying this invention.

Fig. 2 is an edge view of said wrench.

Fig. 3 is a plan view of said wrench partially 30 broken away with certain of the parts shown in dotted lines to indicate the open position of the clamping jaw.

Fig. 4 is a cross section taken on line IV—IV of Fig. 1, and,

35 Fig. 5 is an irregular cross sectional view taken on line V—V of Fig. 1.

Throughout the several views, like reference characters refer to similar parts and the numeral 10 designates a body portion, preferably 40 elongated and tapered to present a narrow end portion 12 for convenience in positioning the wrench, where other objects might prevent the insertion of a broader tool.

This body portion is relatively thin as indicated, and is provided at its narrowed end portion with an opening 14, having parallel side walls 16 interconnected at their outer ends by a substantially V-shaped wall 18. To facilitate proper gripping, wall 18 is provided with teeth 20.

The inner portion 22 of body 10 is thicker than the outer portion thereof and is provided with a longitudinal opening 24, the side walls of which are extensions of the side wall 16 of opening 14. This opening is adapted to receive a jaw 26 which is longitudinally movable therein. The outer end of jaw 26 is preferably provided with a shallow V-shaped cavity 28 having teeth 30.

60 The inner end of said jaw is transversely notched at 32 to receive the operating end 34 of hand lever 36 which is pivoted at 38 to one side of the longitudinal axis of said body portion.

This hand lever 36, together with the stationary hand grip 40, which is integral with said body portion, serves as a convenient means whereby the wrench may be manipulated and the jaw 26 moved to securely clamp any article positioned 5 in opening 14.

It will be noted that by means of this particular type of hand grip and lever, the body portion of the wrench is definitely under control, also the jaw 26 may be easily moved in either direction.

10 To make it more convenient for the operator to manipulate the wrench when the article to be gripped is positioned on a substantially planar surface, for example the fittings on a battery terminal post, the body is preferably arcuate, 15 as clearly shown in Fig. 4. Also the jaw is correspondingly curved. It is very evident that the degree of curvature might be varied through any reasonable range of radii. Referring to opening 14 which may be varied by simply moving the jaw 26, as described above, it will be noted that the opening produced when the jaw is retracted, is substantially hexagonal in shape.

When an article of circular cross section is 25 being gripped, it will be observed that the jaw end structure and wall 18 will cooperate to engage said circular area at four points thereby producing an effectual gripping contact without undue injury to the article.

30 The positioning of jaw 26 within the opening 24 with its side walls bearing against walls 16, presents an extremely efficient movable jaw due to the fact that it is definitely held against movement relative to the body portion. The inner end of opening 24 is closed by means of a spring 35 clip 42 having detents 44, which are adapted to be snapped into position to engage openings 46.

Having thus described the invention, what is 40 claimed as new and desired to be secured by Letters Patent is:

A wrench comprising a unitary body member having a longitudinally curved relatively thin outer portion with a work receiving opening, having its opposite longitudinally curved side 45 walls in parallel relation, formed transversely therethrough; a relatively thick central portion of said body member having a longitudinally curved hole formed therethrough with its longitudinal side walls in curved alignment with and in planar relation respectively with said parallel side walls of said work receiving opening; a longitudinally curved jaw portion in said curved hole of said body portion to conform to said curvature thereof and to the curvature of said thin portion of the body member; and a pivoted hand member 50 operable to move said jaw into and out of said work receiving opening to vary the area thereof.
